FURMAN D. SPEAR, OF NEW YORK, N. Y., ASSIGNOR TO ARMSPEAR MANUFACTURING CO., OF NEW YORK, N. Y., A CORPORATION OF NEW YORK.

SIGNAL-LAMP.

1,314,097.

Specification of Letters Patent. Patented Aug. 26, 1919.

Application filed June 27, 1918. Serial No. 242,150.

To all whom it may concern:

Be it known that I, FURMAN D. SPEAR, a citizen of the United States of America, residing at New York city, county and State of 5 New York, have invented a new and useful Signal-Lamp, of which the following is a specification.

My invention relates to signal lamps for railroad use, particularly of the type termed 10 "classification lamps". Structurally, it is essentially an improvement upon the lamp shown and described in my former Patent #816,509 of March 27th, 1906. The object of the present invention is to provide in a 15 classification lamp novel features of construction whereby it may be readily adjusted and put in condition for giving the desired signal. Classification lamps are located on the front end of locomotives and 20 motor trains, and are arranged to throw a light directly ahead and a corresponding light laterally at the outer side of the train, one of said lamps being provided on each 25 side of the locomotive or motor. When the light which is projected ahead and laterally by each lamp is white, it indicates that the train is an "extra". When there is no light it indicates that the train is a "regular". When the light is green, it indicates that the 30 train is in "sections".

Ordinarily, different lamps are required for these different signaling purposes. By my improved construction, a single lamp may be used to indicate these three different 35 conditions.

In the drawings:

Figure 1 is a vertical section of my improved classification lamp mounted upon a suitable bracket.

40 Fig. 2 is a horizontal section thereof through the center of the lens.

Fig. 3 is a perspective view of one form of the lamp support or bracket.

1 represents a bracket which may be of 45 any suitable construction designed to support the lamp and hold it in the desired position. 2 represents the base of the lamp, which, in this particular case, is of circular outline and is designed to slip into the 50 opening in the ring of the bracket 1 and to be held in any suitable way against rotation as by a pin 3 carried by a spring 4, the pin being projected through the ring of the bracket and into a hole in the base of the 55 lamp adjacent thereto when the lamp is in

place. As shown in the drawings, in Fig. 1 the lamp base 2 may have two oppositely positioned holes for the reception of the pin 3 so that the lamp may be held in either one of two positions 180° apart. 5 represents a 60 burner of any suitable type as the source of light. 6 represents the main body of the lamp. In this particular case, 7-7 represent plain white glasses or lenses which are arranged 90° apart in openings in the main 65 body 6. 8-8 are green glasses or lenses which are located diametrically opposite to the two white lenses. Assuming that the lamp shown in Fig. 2 is placed on the front end of a locomotive or motor at the right hand 70 side, the front lens and the right-hand or outside lens will show white. Obviously, to prevent confusion, the other lenses should be hooded or shielded in some manner suitable to prevent light from passing there- 75 through. To that end, I provide a shield comprising opaque plates or shutters 9-9 which are arranged in a vertical plane to stand between one set of lenses and the source of light. The ends of these shutters 80 9-9 are provided with pivot shafts 10-10 which pass out through the lamp body 6 and are provided with one or more operating handles 11-11 which may be conveniently located outside of the lamp, whereby, by 85 turning the handle or handles, the shields may be swung over to hood the green lenses or the white lenses at will. In the particular form shown in the drawings (Fig. 2) the shields 9-9 are positioned to cut off the 90 light from the green lenses, hence, with the lamp mounted as aforesaid, the signal lamp would indicate, if lighted, that the train was an "extra". If it should be desired to indicate that the train was in "sections" the 95 spring held pin 3 would be withdrawn and the lamp body turned 180° so as to present the green lenses at the front and outside of the train and the shutters or shields 9-9 would then be turned over or reversed so as 100 to cut off the light to the white lenses, then located at the rear and inner side. If the train is a "regular", the burner could be removed or the light extinguished. Thus, by 105 this comparatively simple arrangement I am able to provide in a single structure means for indicating any one of the three signals characteristic of "classification" lamps. Obviously, the structure of the lamp must be such that it can be turned angularly in the 110

bracket so as to position the desired lenses for the proper signaling effect, and it is also essential that the shields shall serve to cut off the light from two lenses at the rear and 5 inner side of the lamp, otherwise confusion would result. The shield 9-9 may be made of comparatively thin and light sheet metal, the inner side of which may be polished if desired to serve to reflect and intensify the 10 light projected through the lenses in use.

It should be understood that various modifications in the details of construction may be resorted to without departing from the spirit and scope of this invention, and 15 that I have attempted herein to describe and illustrate only one preferred form of said invention.

What I claim is:

1. In a lamp, a body having two sets of 20 oppositely arranged light openings with glasses of corresponding color in one set and glasses of another color in the other set, both glasses of one set being arranged adjacent to each other, means for supporting the lamp for angular adjustment to present the desired set of glasses in the desired position, a source of light within the body, with means mounted within the lamp body and movable therein for cutting off the rays of light from 25 the source of light to one or the other set of glasses at will.

2. In a lamp, a body having two sets of oppositely arranged light openings with glasses of corresponding color in one set and 35 glasses of another color in the other set, both glasses of one set being arranged adjacent to each other, means for supporting the lamp for angular adjustment to present the desired set of glasses in the desired position, 40 a source of light within the body, with movable means within the lamp body for cutting off the rays of light from the source of light to one or the other set of glasses at will, said means comprising a shutter pivotally mounted in said lamp body.

3. In a lamp, a body having two sets of oppositely arranged light openings with glasses of corresponding color in one set and glasses of another color in the other set, both 50 glasses of one set being arranged adjacent

to each other, means for supporting the lamp for angular adjustment to present the desired set of glasses in the desired position, a source of light within the body, with movable means within the lamp body for cutting off the rays of light from the source of light to one or the other set of glasses at will, said means comprising a shutter pivotally mounted in said lamp body in a substantially horizontal plane. 55

4. In a lamp, a body having two sets of oppositely arranged light openings with glasses of corresponding color in one set and glasses of another color in the other set, both glasses of one set being arranged adjacent to each other, means for supporting the lamp for angular adjustment to present the desired set of glasses in the desired position, a source of light within the body, with movable means within the lamp body for cutting off the rays of light from the source of light to one or the other set of glasses at will, said means comprising a shutter pivotally mounted in said lamp body in a substantially horizontal plane, and means external of the lamp body for operating said shutter. 60

5. In a lamp, a body having two sets of oppositely arranged light openings with glasses of corresponding color in one set and glasses of another color in the other set, both glasses of one set being arranged adjacent to each other, means for supporting the lamp for angular adjustment to present the desired set of glasses in the desired position, a source of light within the body, with movable means within the lamp body for cutting off the rays of light from the source of light to one or the other set of glasses at will, said means comprising a shutter pivotally mounted in said lamp body in a substantially horizontal plane, and means external of the lamp body for operating said shutter comprising a handle connected to one end of the pivotal portion of said shutter. 85
